The ornamental design for a combined transmitter and receiver for monitoring babies, as shown and described.

DESCRIPTION

FIG. 1 is a perspective view of a combined transmitter and receiver for monitoring babies, showing my new design, the transmitter being shown to the left of FIG. 1 and the receiver to the right of FIG. 1;

FIG. 2 is a front elevation view of the transmitter portion thereof;

FIG. 3 is a left side elevational view of the transmitter portion;

FIG. 4 is a right side elevational view of the transmitter portion;

FIG. 5 is a top plan view of the transmitter portion;

FIG. 6 is a bottom plan view of the transmitter portion;

FIG. 7 is a front elevational view of the receiver portion;

FIG. 8 is a left side elevational view of the receiver portion;

FIG. 9 is a right side elevational view of the receiver portion;

FIG. 10 is a top plan view of the receiver portion; and,

FIG. 11 is a bottom plan view of the receiver portion.
